UNITED STATES PATENT OFFICE

PAUL A. JONES, OF JONESVILLE, MICHIGAN

BRUSH

Application filed June 13, 1929. Serial No. 370,583.

This invention relates to improvements in brushes, brooms, and devices of similar character and nature, usable with or without a handle, and more particularly to devices of this nature, in which the bristles are effectively supported and maintained substantially in their initial position while the device is in use.

This invention is designed to overcome defects and objections in a provision of a brush or device of like character having means which are simply and easily mountable therein for stiffening or supporting the bristles.

The invention also seeks to provide means for stiffening the bristles of a brush or the like, which means may be flexible or rigid, and mounted at any desired angle with respect to the bristles.

While some of the more salient features, characteristics, and advantages, of a machine embodying this invention have been above pointed out, others will become apparent from the following disclosures.

The invention includes these and other features of construction and combinations of parts hereinafter described, and shown in a preferred form in the drawings, as more particularly indicated by the claim.

On the drawings:

Figure 1 is a fragmentary end view in elevation of a device embodying principles of the present invention.

Figure 2 is a fragmentary transverse sectional view of the device shown in Figure 1, looking in the same direction as in Figure 1.

Figure 3 is a fragmentary longitudinal sectional view taken substantially along line III-III of Figure 2.

Figure 4 is a reduced fragmentary view similar to Figure 2, showing a slightly different form of construction.

As shown in the drawings:

In the illustrated embodiment of this invention, there is shown a brush of the type commonly termed a "push brush", comprising a relatively rigid back or bristle holding member 1, to which a handle 2 is secured in any desired manner, or imbedded therein as shown more clearly in Figure 2. In this instance, the back or bristle holding member 1 is pro-

vided with a plurality of pockets or recesses 3 in the under side thereof in which bristles 4 are secured in any desired manner, as for instance, by rust proof staples engaging a fold in the bristles.

At any desired locations among the bristle pockets 3, other pockets 5 are provided for receiving therein portions of means for stiffening or supporting the bristles 4. The stiffening means, in this instance, comprise an elongated member or wire 6 extending to any desired distance relative to the bristle tips and provided with upwardly turned ends 7 the extremities of which are imbedded in the pockets 5. As shown in the drawings, the bristles are mounted in orderly rows and the stiffening members 6 run parallel with the rows and are substantially hidden by the bristles. Obviously, any desired number of stiffening members may be utilized. These stiffening members maintain the bristles in substantially their initial position at all times and effectively prevent the bristles from becoming set in an oblique and distorted position which would materially detract from the utility of the brush. The stiffening members also aid in supporting the bristles when the brush is subjected to heavy duty, for instance, if used on machines or in similar places.

In Figure 4 I have shown a stiffening member 6a provided with upwardly turned ends 7a imbedded in relatively oblique pockets 5a, the stiffening member being disposed at an acute angle relatively to the backing member 1. It is sometimes desirable to have stiffening members disposed at an angle to the backing member and to the bristles. It is also desirable, as occasion demands, to have the stiffening members of somewhat resilient material so that they would give or bend slightly if the bristles are subjected to abnormal strain as indicated by the dotted lines in Figure 4. It should be noted, of course, that the stiffening members need not be disposed parallel to the rows of bristles but may be disposed in any desired position and at any desired angle relative to the backing member 1 regardless of the manner in which the bristles are mounted or disposed.

Although in the present instance, the stiffening members are shown as made of wire, it is to be clearly understood that this is merely for the purpose of clearly disclosing the present invention, and that the stiffening members 5 may be made of any desirable material, rigid or resilient. Further, it should be noted that the present invention may be embodied in any form of brush, broom, or similar device. It should also be noted that 10 where the term "bristles" is used herein and in the appended claim, the same is to mean bristles, fiber, strips, or the like made of any desirable material.

15 From the foregoing it is apparent that I have provided a brush in which the bristles are effectively stiffened or supported by means tending to maintain them in their initial position at all times, the means being 20 easily mountable in a brush or the like, and affording a maximum of durability without adding materially to the cost of manufacturing the article as a whole, the article being very economically manufactured.

25 I am aware that many changes may be made and numerous details of construction may be varied through a wide range without departing from the principles of this invention and I, therefore, do not purpose limiting 30 the patent granted hereon otherwise than necessitated by the prior art and as defined by the scope and spirit of the appended claim.

I claim as my invention:

As an article of manufacture, a brush including 35 a head member having a plurality of pockets therein, bristles secured in some of said pockets, a plurality of elongated U-shaped wires concealably disposed among said bristles of less width than said head and 40 arranged tending to maintain certain of said bristles in substantially their initial position, said wires having their end portions embedded in other of said pockets.

In testimony whereof I have hereunto subscribed my name at Jonesville, Hillsdale County, Michigan.

PAUL A. JONES.
